UNITED STATES PATENT OFFICE.

WARREN P. GOLDTHWAITE, OF BURLINGTON, IOWA.

ATTACHMENT FOR PUNCHES.

SPECIFICATION forming part of Letters Patent No. 608,256, dated August 2, 1898.

Application filed June 25, 1897. Serial No. 642,344. (No model.)

To all whom it may concern:

Be it known that I, WARREN P. GOLDTHWAITE, a citizen of the United States, residing at Burlington, in the county of Des Moines 5 and State of Iowa, have invented a new and useful Attachment for Punches, of which the following is a specification.

The invention relates to attachments for punches especially adapted for use by conductors or other officials of a railroad.

The object of the present invention is to provide a punch with a magnifying-glass to be used for deciphering small printed matter on a ticket, partly-obliterated writing or signatures thereon, and other matter on the ticket, as well as for magnifying purposes generally, the attachment being so arranged or combined with the punch that when the latter is held in position for operating on a 20 ticket the magnifying-glass may be used without changing the position of the punch in the hand.

A further object of the invention is to arrange the magnifying-glass within the limits 25 of the punch without interfering with the operation of the same and to avoid any projecting parts, so that the instrument may be readily carried in the pocket without liability of injuring the magnifying-glass.

Another object of the invention is to enable 30 the spring, which holds the punch in position for operating on a ticket, to be also employed for retaining the lens in place.

The invention consists in the construction 35 and novel combination and arrangement of parts hereinafter fully described, illustrated in the accompanying drawings, and pointed out in the claim hereto appended.

To enable others to understand my invention, I have illustrated the same in the accompanying drawings, forming a part of this specification, and in which—

Figure 1 is a perspective view of a punch, showing my attachment applied thereto. Fig. 45 2 is a sectional elevation showing the preferred construction by which the pressure-spring and the lens are held in position within the instrument by a single stem or rod. Fig. 3 is a detail view of the stem or rod detached 50 from the instrument.

Like letters of reference denote correspond-

ing parts in all the figures of the drawings, referring to which—

A designates the punch. B is the lens, and C is the holder or frame by which the lens is attached to the punch within the limits of the levers or handles thereof.

The punch A may be of any suitable construction, as the punch proper forms no part of my present invention. As shown in the drawings, the punch consists of two levers or members constructed to form jaws at one end and to cross one another to adapt the members to be pivoted together and thus form the handles *a a*, by which the implement can be readily grasped within the hand, so as to force the jaws together to force the punch-die G through the ticket fitted in the slot *g*.

According to my invention I provide an attachment by which small, obscure, or partly-obliterated matter on a ticket or other object 70 may be enlarged and made visible to the conductor or other person using the instrument. The attachment comprises the lens B and the frame or holder C, which receives the lens 75 within itself and which is attached to the inner face or side of one of the handles *a* of a suitable form of punch, whereby the magnifying attachment is arranged to be inclosed within the limits of the punch, and it does 80 not interfere with the operator in grasping and manipulating the instrument.

The lens-holding means is combined with the pressure-spring to serve as a guide therefor. The invention embraces a novel construction of the rod or stem D—that is to say, the rod consists of a straight elongated shank *d* and a loop or eye *d'*, which is bent to a shape proper to receive within itself the lens B. The extremity of the stem or rod beyond 85 the lens-holding loop *d'* is attached rigidly to the outer end of one of the handles *a* of the instrument; but the other end of said stem D is fitted loosely in a slot or opening *e*, provided in the other handle *a*, at a point close 90 to the fulcrum of the two members or levers of the punch. The straight portion of the stem or rod is thus arranged to extend diagonally across the space between the two handles, and one end of said rod is fast with one 95 of the handles, while the other extremity thereof is loosely or slidably connected to the 100

other handle, whereby the stem is adapted to have a limited endwise movement when the members or levers are forced together or spread apart. On the straight shank *d* of the stem or rod is loosely fitted a coiled spring *E*, one end of which is seated against the loop *d'* of the stem. The other end of the coiled spring bears against the handle *a* at the point where the free end of the stem plays loosely in said handle, and thus the spring operates to press against the two handles to normally force them apart.

From the foregoing description it is obvious that the stem or rod serves as the means for fastening the lens *B* to the instrument within the handles thereof, and it also serves the purpose of holding the pressure-spring *E* between and in operative relation to the two handles of the instrument. The loop or eye *d'* of the stem fits tightly around the peripheral edge of the lens, except for a short distance, where the lens abuts or bears against the inner face of the handle, to which the outer extremity of the rod or stem *D* is attached rigidly in a suitable way.

The coiled spring, besides operating to hold the handles normally separated, also serves to cause the eye or loop to clamp the lens.

It will be observed that I have combined a magnifying-lens with a punch in such a way that the lens is not in any way obstructed or obscured by the punch-handle and the means by which it is attached to said handle, and at the same time the lens and its holding means

are arranged within the limits of the instrument to be out of the way when the instrument is grasped and operated.

I am aware that changes in the form and proportion of parts and in the details of construction may be made without departing from the spirit or sacrificing the advantages of my invention, and I therefore reserve the right to make such changes and alterations as fairly fall within the scope of my invention.

Having thus fully described my invention, what I claim as new, and desire to secure by Letters Patent, is—

The combination with a punch, of a stem bent upon itself at its rear portion to provide a divided loop or eye and secured at the rear side of the eye to the adjacent handle, said stem having a straight diagonal portion extending across the punch to the other handle and slidably connected with the same, a lens arranged within the loop or eye, and a coiled spring mounted on the straight diagonal portion of the stem and interposed between the eye or loop and the opposite handle, whereby the handles are held normally separated and the lens is also clamped within the said loop or eye, substantially as described.

In testimony that I claim the foregoing as may own I have hereto affixed my signature in the presence of two witnesses.

WARREN P. GOLDTIWWAITE.
